United States Patent Office.

SAMUEL THOMPSON, OF BALLSTON SPA, NEW YORK.

Letters Patent No. 75,599, dated March 17, 1868.

METHOD OF HANGING SIEVES AND SCREENS.

The Schedule referred to in these Letters Patent and making part of the same.

TO ALL WHOM IT MAY CONCERN:

Be it known that I, SAMUEL THOMPSON, of Ballston Spa, in the county of Saratoga, and State of New York, have invented a new and improved Agitating Motion; and I do hereby declare that the following is a full, clear, and exact description thereof, which will enable those skilled in the art to make and use the same, reference being had to the accompanying drawings, forming part of this specification, in which—

Figure 1 is a transverse vertical section of a screen or riddle provided with my improvements.

Figure 2 is a plan view of the screen.

Figure 3 is a detail view of the eye and pin of the rod modification.

Similar letters of reference indicate corresponding parts.

This invention relates to the production of a certain violent agitating motion applicable to a variety of purposes, as the screening of salt, where the riddle or screen frequently becomes clogged or choked, and to which it is especially liable when the salt is green or damp.

In the manufacture of confectionery of certain kinds, pellets of candy are jolted or agitated in trays, to obtain a certain desirable finish and appearance. These trays are suspended from two lateral points, and the agitation is performed by an attendant, who pushes and jerks the tray in a peculiar manner. This operation is laborious, and requires a considerable degree of skill in the operation before it can be performed properly. The bulky and heavy character of coal requires that it be thrown against a riddle standing at an angle with the ground, in order to screen it properly and with the least labor. In the manufacturing arts there are many cases where a certain jolting agitation is requisite, and in these, and those above cited, my invention will be found applicable and advantageous.

In the accompanying plate of drawings a salt-riddle or screen is shown suspended by chains according to the principle of my invention; and which will now be specifically described, both as to its construction and operation, and which will illustrate the application of my improved device for obtaining the desired agitating motion.

The general frame A is supported by legs B. Uprights from the said frame A support the cross-beams D, from which the screen-frame e is suspended by four pairs of chains, lettered b and a, as shown. For the chains there may be substituted lines or cords, it being only required that the same be of a flexible character, as will be shown. The sieve or wire netting is shown at E. The frame A and beam D are mere expedients, and form no part of the invention, and may be modified or replaced by other arrangement of parts, as occasion demands. The frame e of the screen is suspended by four pairs of chains, as above stated, there being one pair at or near each corner thereof, as shown. These chains are affixed to the beam D, each pair depending from or near the same point, as shown. The two chains of each pair diverge at an angle, as shown, and this divergence is the feature which conduces to the peculiar jolting agitation of the frame e, to which the chains are attached, when the said frame is moved quickly to and fro, as will be more fully set forth. When the frame is moved in one direction, as in the direction of the obvious incline of the screen, as shown, its weight will be sustained by all of the chains until it passes a certain point in its travel, when the hindmost chains of each pair will become slack by the acuteness of the angle formed by the forward chains and the plane of the frame e, which angle the hindmost chains subtend when both chains of each pair are straight; but when the frame is moved, the angle between the forward chains and the plane of the frame becomes more acute, and thus relieves the hindmost chains from supporting the frame. This transmission of the weight of the frame to the forward chains is attended with a jerk or jolt of the frame when the motion of the latter is brisk. When the frame is returned, or drawn in the contrary direction, the hindmost chains (now the forward chains) tighten as the angle aforesaid becomes more obtuse, and when the movement of the frame is brisk, the said chains become straight, and take the weight of the frame e with a jerk, which is peculiarly desirable for screening, sifting, or other purposes, as aforesaid.

In fig. 1 the frame is being moved upward, or against the obvious incline. The forward chains b having become straight, take the weight of the frame. The hindmost chains are then slack, as shown. In the reverse motion the red chains exhibit the operation, the chains b having become slack, as shown at b', and the chains a having taken the weight of the frame, as shown at a'.

Coupled with the intermittent jerking or jolting of the frame, as above described, the said frame is accorded

an up-and-down or vertical motion, (keeping parallel to itself at each point of the said vertical motion,) which, in concert with its ordinary to-and-fro motion, (given by the power applied to g ,) conduces to a compound agitating motion, which is peculiarly efficient in such operations as sifting, screening, or abrading pellets or particles of matter, or accomplishing the commingling of materials or compounds.

Modifications of my invention may be made in several ways, the principle, however, being the same, some of which I will describe.

In the place of suspending the frame e by chains or flexible cords, four pairs of rods, $d d'$, diverging from points $h h$, may be used to support the frame from beneath it, the said rods being each provided with a slotted head, j , to enclose a pin, i , on the frame e , as is better shown at the detail view of fig. 3. The operation of these rods would be analogous to that of the chains before described, and requires no separate description.

Again, the frame e may be made to rock, so to speak, upon the ends of those rods $d d'$, or the said rods, with the eye and pin-device, or any suitable equivalent thereof, may be substituted above the frame for the flexible chains, the travel of the pins i in the eyes j taking the place of the slackened chains.

I have thus set forth in detail what I consider to be the best means of producing the peculiar effective motion, but in all the equivalent modifications generally described, the principle of their action is identical with that first described.

When used for salt-screens, the jerking motion is highly effective to keep the screen from choking, which it is liable to do with damp or even dry salt. In some instances two pairs of chains or rods attached to the frame or tray, so as to balance it, will be quite sufficient, as in the agitating of confectionery before mentioned, but with heavier or more bulky matter four pairs will be more suitable.

This invention has been proven by practical trial to operate in the manner above set forth.

I claim as new, and desire to secure by Letters Patent— Suspending or supporting a frame, e , or tray, or box, or other vessel by two or more pairs of diverging rods or chains, substantially as shown and described, or the equivalent thereof, for the purpose of producing in the said frame, tray, box, or other vessel the peculiar compound agitating motion, as above set forth.

The above specification of my invention signed by me, this 23d day of January, 1868.

SAM'L THOMPSON.
